UNITED STATES PATENT OFFICE.

JACOB LUXEM, OF RACINE, WISCONSIN.

FANNING-MILL.

SPECIFICATION forming part of Letters Patent No. 267,699, dated November 21, 1882.

Application filed March 15, 1882. (No model.)

To all whom it may concern:

Be it known that I, JACOB LUXEM, of Racine, in the county of Racine, and in the State of Wisconsin, have invented certain new and useful Improvements in Fanning-Mills; and I do hereby declare that the following is a full, clear, and exact description thereof.

My invention relates to fanning-mills, and will be fully described hereinafter.

10 In the drawings, Figure 1 is a vertical longitudinal section of my device, and Fig. 2 is a horizontal section on line $x x$, Fig. 1.

A is the first hopper, that takes the wheat from the floor. In this hopper I have a shoe, 15 A', containing sieves $a a'$. The sieves $a a'$ have perforations sufficiently large to permit the grains of wheat to fall through, while the perforations in sieve a' are too small for wheat to pass through, and will only permit the dust 20 and small seed to settle through to a slanting floor, b, and from the bottom of this floor, on one side, I lead a pipe, c, to the center of a drum, B. The wheat, when it leaves the sieves $a a'$, falls onto a slanting shelf, a^2 , and 25 is conveyed to openings $d' d'$ at the bottom of each end of the shelf, and thence down into the hopper D; but before it reaches the openings d' it encounters a blast from the fan-wheel E, guided by board b' , through a narrow 30 opening, d , which relieves it of its dust as it falls to the hopper. The shelf a^2 , it will be observed, slants downward from its center to its ends, to 35 guide the wheat so that it may fall in front of the spouts D'; and its front edges are inclined to meet the angle of the board a^3 , so as to deflect the blast through the wheat into the spouts D', whence the dust is carried from the wheat to the drum B, in which is a fan-wheel, C, that draws it into the drum from said spouts

D' and forces it out through a spout, F. To 40 give additional force to the fan-wheel C, I may make a partition in its center. The dust from chamber b is also drawn into the drum B by the wheel C, a spout, c, serving to convey the dust from the lower corner of the floor of said 45 chamber.

The rest of the machine (not referred to by letter) is old, and its operation is too well known to need description here.

The shoe A' is to be provided with any well-known shaking mechanism, so as to be constantly agitated.

What I claim as my invention is—

1. The combination, in a fanning-mill, of the hopper A, having shaking-shoe A', containing 55 fine and coarse sieves, with the fan-wheel E, drum B, fan-wheel C, spouts D' D' and F, hopper D, and slanting shelf a^2 , and the casing having an opening to conduct the air from fan-wheel E through the wheat into drum B, substantially as shown and described, and for the purpose set forth.

2. The combination, in a fanning-mill, of the hopper A, having shoe A', provided with fine and coarse sieves, and a dust-chamber beneath them, with the drum B, fan-wheel C, spout F, and a pipe, c, extending from the lower corner of the dust-chamber to the drum B, substantially as shown and described, and for the purpose set forth.

In testimony that I claim the foregoing I have hereunto set my hand this 24th day of February, 1882.

JACOB LUXEM.
